UNITED STATES PATENT OFFICE

2,085,289

RAILWAY TRUCK

Starley F. Beasley, Tulsa, Okla., assignor, by
mesne assignments, to Chicago Railway Equipment
Company, Chicago, Ill., a corporation of
Illinois

Application May 31, 1932, Serial No. 614,570

29 Claims. (Cl. 188—210)

This invention relates to railway trucks and, more particularly, to a device adapted to normally underlie an associated brake beam to serve as a support therefor upon failure of the usual supporting means.

The principal object of my invention, generally considered, is to provide a safety device adapted to be movably connected to the side frame of a railway vehicle or truck so that it may be positioned to underlie a brake beam to serve as a safety support therefor, or swung out of the way so as not to interfere with the application or removal of said beam.

Another object of my invention is the provision of a safety device adapted to be pivotally mounted between flanges extending from the tension member of an associated side frame so as to extend inwardly therefrom and normally underlie an associated brake beam, or be swung toward said frame out of the way of said beam so as not to interfere with the application or removal thereof.

A further object of my invention is to provide a safety device for brake beams including a bracket involving a web adapted for connection with an associated side frame and flanges extending therefrom, and a safety bar pivotally mounted between said flanges for either underlying an associated brake beam or being swung out of the way toward the associated frame.

Other objects and advantages of the invention relating to the particular arrangement and construction of the various parts will become apparent as the description proceeds.

Referring to the drawing illustrating my invention, the scope whereof is defined by the appended claims:—

Figure 1 is a fragmentary side elevation of the inner portion of a railway vehicle side frame with one embodiment of my invention applied thereto, the associated spring plank and brake beam being shown in section.

Figure 2 is a fragmentary horizontal sectional view showing my brake beam safety bar in operative position in full lines and in inoperative position in skeleton lines.

Figure 3 is a fragmentary view corresponding to Figure 1, but showing a modified form of my invention, with the safety bar removed.

Referring to the drawing in detail, like parts being designated by like reference characters, and first considering the embodiment of my invention illustrated in Figures 1 and 2, there is shown a portion of a railway vehicle or truck side frame comprising a tension member 2 and bolster guide columns 3, only one of which is illustrated, up-

standing therefrom for spacing intermediate portions thereof from the compression member (not shown). The tension member 2 may comprise flange or shelf portions 4 extending inwardly from the inner face of the inner wall, web or flange 5 of said tension member, and serving to extend the spring plank or spring seating area 6 of the frame on which rests the spring plank 7.

Portions 5 and 6 alone or in combination with spring plank 7 comprise the usual spring seat structure.

In the present embodiment of my invention, the flange 4 is extended to provide an auxiliary shelf portion beneath the guide columns 3, from whence it is diverted upwardly, as indicated at 8, to taper or provide generally triangular reinforcing gusset portions, disposed at an angle to the flange 4 and which finally merge into the diagonal end portions 9 of the tension member. Underlying the flange portions 4 and 8, and spaced therefrom, are angular flange portions 10 forming, with the flange portions 4 and 8, a pocket 11 receiving the foot of a safety bar 12. The flanges 4 and 10, and the foot of the safety bar 12, are, in the present embodiment, apertured, as indicated at 13, 14, and 15, to normally receive and form bearings for a pivot pin 16, by means of which the bar 12 is pivoted to the frame 1 so that it normally underlies the associated brake beam 17 to serve as a support therefor in case the usual supporting beam means 18 should fail, while at the same time it is adapted to be swung toward the frame 1, as indicated in skeleton lines in Figure 2, so as not to interfere with the application or removal of said beam.

The safety bar, in the present embodiment, comprises portions thereof angularly disposed with respect to one another, so that the foot portion 19 may lie generally parallel to the frame 1 when in normal position, while the body portion 20 extends inwardly and diagonally, terminating in a head portion 21 which provides an upper, preferably flat, surface 22 normally underlying the associated brake beam 17 and in close proximity thereto, so that if the beam should accidentally be torn from its normal fastenings, it will not drop on the track, but will instead be supported on the safety bar 12 and a corresponding supporting device on the other frame, it being understood that although only a portion of one of these truck side frames is illustrated, yet each side frame desirably has two safety bars pivotally mounted thereon so that each of the two brake beams has a bar underlying each end thereof. In order to prevent the bar 12 from unintentional

deflection from normal or operative position, the same is desirably held in position, as by a securing device or cotter 23, which may extend through normally registering apertures 24 and 25 in the 5 foot portion 19 of the bar and the flange 10 of the side frame therebeneath. Undesired removal of the pivot pin 16 may be prevented in any desired manner, but, in the present embodiment, in which the axis thereof is diagonal, so that the bar 10 10 may be swung diagonally upward to lie along the diagonal end portion 9 of the tension member 2, it will be seen that no separate securing means is necessary as the spring plank 7 lies, above the head of, and on the axis of the pin when assembled, and prevents loss or undesired removal thereof.

In the present embodiment, the safety bar 12 is formed as a casting, with a generally upright web 26 extending substantially the full length thereof, 20 the parts of said web comprising the foot 19 and the head 21, however, being angularly disposed with respect to the intermediate portion thereof, as shown most clearly in Figure 2. The intermediate or body portion 20 of the safety bar or 25 casting 12 is generally Z-shape in section, that is, the upper and lower flanges 27 and 28 extend in opposite directions, the upper flange 27 merging into the angularly disposed foot portion of the web 26, and the web portion provided with the 30 brake beam supporting surface 22 at the other end. The lower flange 28 merges into the deflected portion of the web 26 in the head of the casting and is extended beneath the web portion 26 at the foot end to form the flange portion 29 35 which receives the retaining cotter 23. The web 26 is expanded at the junction between the body and foot portions thereof to form the apertured spool 30 which receives the pivot member 16. It will, however, be understood that the bar, if desired, may be of a form different from what is 40 here specifically described.

Referring now to the embodiment of my invention illustrated in Figure 3, a construction is there disclosed which is identical with the previous embodiment, except that the flanges 4^a and 10^a, 45 instead of being integral with the frame or tension member 2^a thereof, are formed as part of a bracket or casting 31, the web 32 of which, from which the flanges 4^a and 10^a extend, being connected to the tension member 2^a of the associated frame 1^a in any desired manner, as by means of rivets 33. In this way, my safety bar may be employed with frames of conventional construction by merely connecting a bracket member thereto 50 and then pivoting the safety bar to said member.

From the foregoing disclosure, taken in connection with the accompanying drawing, it will be seen that I have devised a safety bar secured in place by means intersecting said bar and an associated frame, or flanges extending therefrom, or 55 from a member secured thereto, adapted to either underlie one end of a brake beam for catching said beam in case the usual supporting means should fail, or be swung out of operative position to avoid interference with the application or removal of the beam, means being provided for securely holding the bar in operative position, and said bar being adapted for use either with a frame especially designed for the pivotal mounting thereof, or with a conventional frame to 60 which a supporting bracket member is secured.

Although preferred embodiments of my invention have been illustrated, it will be understood that modifications may be made within the spirit and scope of the appended claims, and although

the beam 17 is shown with a plate 34 riveted thereto and overlying the supporting surface 22 of the bar 12, I do not wish to be limited to this showing.

I claim:—

1. In a railway truck, in combination with a truck side frame, a brake beam, a safety bar normally underlying said beam for supporting the same upon failure of the usual supporting means, and means pivotally connecting said bar to said frame so as to adapt the former to be swung out of the way to allow for application or removal of said beam.

2. In a railway truck, in combination, a side frame comprising a tension member, flanges extending from the inner face of said member, a brake beam, a safety bar with a portion received between said flanges, and means intersecting said flanges and bar for pivotally connecting the bar and frame, said bar normally extending inwardly to underlie said brake beam and adapted to be swung outwardly toward the frame to permit application or removal of said beam.

3. In a railway truck, in combination, a side frame comprising a tension member, flanges extending from the inner face of said member, a brake beam, a safety bar with a portion received between said flanges, and means pivotally connecting said bar and frame, said bar normally extending diagonally to underlie said brake beam and adapted to be swung toward the frame to permit application or removal of said beam, said bar being provided with a flange normally lying adjacent a corresponding flange on the frame and aperture for receiving retaining means.

4. In a railway truck, in combination, a side frame, a bracket connected to said frame and provided with flanges extending therefrom, a brake beam, a safety bar with a portion received between said flanges, and means intersecting said flanges and bar for pivotally connecting said bar and bracket, whereby said bar normally underlies the beam and is adapted to be swung out of the way for application or removal of said beam.

5. A side frame for a railway truck comprising a tension member, and a plurality of flanges extending diagonally and inwardly from the inner face thereof to provide a pocket for a brake gear safety device and provided with registering apertures for receiving a pivot member for said device.

6. A brake beam safety bar comprising head, body and foot portions, all of said portions having a web and flanges, the portions of said web in said head and foot portions being angularly disposed with respect to the remainder, the flanges of the body portion of said web extending in opposite directions from the upper and lower edges thereof, and the portion adjacent the junction between said body and foot portions being apertured for the pivotal mounting of said bar.

7. A side frame for a railway truck comprising a tension member with bolster guide columns upstanding therefrom, an auxiliary shelf portion extending inwardly from the top of the lower section of said tension member beneath a guide column, and a reinforcing gusset extending laterally from said section, disposed at an angle to the upper surface of said shelf portion, extending below the same, and continued to finally merge into said tension member.

8. In a railway truck, in combination, a side frame, a casting mounted on said frame and provided with flanges extending therefrom, and disposed one above the other, a brake beam, a safety bar with a portion received between said flanges,

5 and means intersecting said flanges for securing said bar to said casting, whereby the free end portion of said bar normally underlies the beam and is adapted to be moved out of the way for application or removal of said beam.

9. In a railway truck, in combination, a side frame comprising a tension member, flanges extending from the inner face of said member and disposed one above another, a brake beam, a safety bar with a portion received between said flanges, and means intersecting said flanges for connecting the bar to the frame, said bar normally extending inwardly so that its free end portion underlies said brake beam and is adapted to be moved out of the way to permit application and removal of said beam.

10. In a railway truck, in combination with a side frame, a brake beam, a device with an end portion normally underlying, and spaced a slight 20 distance below, one end portion of said beam to serve as a support therefor upon failure of the usual supporting means, and means passing from top to bottom through said device and a portion of said frame so as to connect it thereto, while adapting said device to be moved out of the way to permit application or removal of said beam.

11. A side frame for a railway truck comprising a tension member, and a plurality of flanges extending inwardly from the inner face thereof 30 to provide a pocket for mounting a safety device, and provided with registering apertures for receiving a diagonally extending pivot member for said device.

12. In a railway truck, in combination, a side 35 frame having a tension member with bolster guide columns upstanding therefrom, and means extending inwardly from said tension member to underlie and serve as safety means for the adjacent ends of brake beams, said means comprising auxiliary shelf portions extending inwardly from the inner surface of the tension member beneath said guide columns, and reinforcing generally triangular gussets angularly disposed with respect to the upper surfaces of said shelf portions, extending therefrom, and continuing to 45 finally merge into said tension member.

13. In a railway truck, a side frame member, a brake beam, a device secured to said member and movable thereon, without being detached 50 therefrom, to a position underlying and safeguarding said beam against dropping or to a position in which said beam may be dropped and removed from the truck.

14. A structure as described in claim 13, which 55 also includes detachable means for holding said device in the first-mentioned position.

15. In a railway truck, a framing member, a 60 brake gear, a safety device pivotally mounted on said framing member and movable about its pivot to a position underlying said gear for supporting the same upon failure of its normal supporting means or to a position out of the way of said gear to allow for application or removal of said gear.

65 16. In a railway truck, a framing member, a brake beam extending substantially from one side of the truck to the other and a safety device pivotally mounted on said member and movable about its pivot to a position underlying one 70 end of said beam, for supporting the same upon failure of its normal supporting means, or to a position out of the way of said beam end to allow for application or removal of said beam.

17. In a railway truck, a side frame, bolster 75 spring seat structure, bearing elements on said

frame, and a pivot pin mounted in said elements, a safety device carried by said bracket elements and movably secured thereto by said pin, a brake beam suspended from said frame, said device being movable from a position underlying and safeguarding said beam to a position out of the way of said pin to facilitate application and removal of said beam, said seat structure holding said pivot pin against removal from said brackets.

18. In a railway truck, a side frame, a brake 10 beam, a hanger suspending said beam from said frame, and an element of restricted width pivoted to said side frame and projecting inwardly therefrom and arranged to underlie the adjacent end portion only of said brake beam to form an individual safety guard therefor or to be swung to a position clear of the beam end to permit the same 15 to be dropped for removal of the beam from the truck.

19. In a railway truck, a side frame, brake 20 beams spaced from each other longitudinally of the truck, individual hangers suspending said beams from said frame, and spaced elements individually pivoted on said side frame and arranged to underlie respectively the adjacent end 25 portions of said brake beams or to be swung independently of each other to positions to permit the respective beam ends to be dropped for removal of the beams from the truck.

20. In a railway truck, a side frame, brake 30 beams spaced apart longitudinally of the truck and said frame, individual hangers suspending said beams from said frame, and spaced elements extending inwardly from said frame independently of each other to individually engage the 35 corresponding end portions of said beams to safeguard the latter against falling on the track in the event of the failure of their respective hangers.

21. In a railway truck, a side frame having a 40 bolster receiving opening and including a column and lower part defining a bottom corner of said opening, and a flange on said side frame projecting inwardly therefrom transversely of the angle of said corner to reinforce the frame and forming 45 individual safety guard structure for the adjacent portion of a brake beam.

22. In a railway truck, a side frame having a 50 bolster receiving opening, a brake beam suspended therefrom, and a flange projecting from 50 said frame and bracing the same at the corner of said bolster receiving opening and extending inwardly from said frame and constituting brake beam safety guard structure.

23. In a railway truck, a side frame comprising 55 a tension member with bolster guide columns upstanding therefrom, a pair of vertically spaced rib-like elements extending transversely of said tension member below one of said guide columns and reinforcing the frame adjacent the angle 60 between said member and column.

24. A structure as specified in claim 23 which 65 also includes a brake gear safety device seated between said elements.

25. In a railway truck, a side frame having a 70 bolster receiving opening and including a tension member and a column, said column and the lower part of said tension member defining a bottom corner of said opening, and lateral flanges extending integrally from the top and bottom respectively of said tension member lower part and extending transversely of the angle of said corner to reinforce the frame.

26. In a railway truck, a side frame, a brake 75 beam suspended from said frame and including a

brake head, and a safety element carried by said frame at a point adjacent the end of said beam and extending inwardly below the bottom of said head and then upwardly to provide a support for engaging the beam members inwardly of said head.

27. A structure as specified in claim 26 in which said safety element is movable about its mounting on said frame to clear said head and beam members to permit lowering of the beam.

28. In a railway truck, a side frame, a brake beam suspended therefrom and including a main longitudinal member of relatively restricted width and a brake head mounted on the end portion thereof, a safety element carried by said frame at a point adjacent the end of said beam and extending inwardly to provide a support for said member inwardly of said head, there being a cooperating element extending transversely of

said beam member to provide a larger bearing for engagement by said support.

29. In a railway truck, a side frame, a brake beam suspended therefrom and including a longitudinal member of relatively restricted width and a brake head mounted on the end portion thereof, a safety element pivotally carried by said frame at a point adjacent the end of said beam and extending inwardly to provide a support for said member inwardly of said head, said element and support being of restricted area to fully clear said beam when swung upon its pivot to an inoperative position, there being a cooperating element extending transversely of said beam member to provide a larger bearing for engagement by said support when the latter is in operative position.

STARLEY F. BEASLEY.
